Inventor
Charles H. Helling

UNITED STATES PATENT OFFICE.

CHARLES H. HELLING, OF OAKLAND, CALIFORNIA, ASSIGNOR OF ONE-HALF TO JOHN H. HERRING, OF PIEDMONT, CALIFORNIA.

MECHANICAL-TARGET RANGE.

Application filed May 3, 1922. Serial No. 558,055.

To all whom it may concern:

Be it known that I, CHARLES H. HELLING, a citizen of the United States, residing at Oakland, county of Alameda, and State of California, have invented new and useful Improvements in Mechanical-Target Ranges, of which the following is a specification.

This invention relates to a target apparatus, wherein is employed an imitation firearm, such as a gun or pistol, so mounted that it can be turned horizontally and vertically to be aimed at any one of several targets or objects disposed on pedestals or other supports arranged at a suitable distance forward of the gun, and which apparatus is provided with a striking device actuated by the trigger of the gun in such a manner that if a correct aim is taken the striking device will indicate a hit by knocking down the target.

The object of the present invention is to generally improve and simplify devices of the character described; to provide an apparatus which permits the use of natural targets, such as birds, beasts, etc.; an apparatus in which the targets are loosely placed on pedestals or other suitable supports, and in which no connection is made with the fire-arm and the striking mechanism actuated thereby, and from which supports they fall or are knocked off by the striking mechanism when a correct aim is taken; an apparatus in which the mechanism is concealed, thereby mystifying the operator and spectators as to the means employed for knocking down the targets; and further an apparatus which is not only amusing in character, but also educational to the extent that skill in aiming and firing is obtained as ordinary gun or pistol practice and without danger, as projectiles and explosives are not required.

One form which my invention may assume is exemplified in the following description and illustrated in the following drawings, in which—

Fig. 1 is a central, vertical, longitudinal section through the apparatus.

Fig. 2 is a detail sectional view of the pistol and a portion of the mechanism actuated thereby.

Fig. 3 is a front view of the pistol.

Fig. 4 is a plan view of the target range.

Fig. 5 is a sectional detail view of the lower end of the pedestal by which the pistol is supported.

Fig. 6 is a cross section of the pedestal 10, said view also showing the bearing bracket 11, in which it turns.

Referring to the drawings in detail, and particularly to Figs. 1 and 2, A indicates in general a base member which in this instance consists of a cover section 2 and a base or bottom section 3. A suitable space 65 is formed between the bottom and the cover section 2 and within this space is mounted a mechanism hereinafter to be described. Disposed at one end of the base or support is a pedestal B, and arranged at the opposite end of the base or support is a plurality of pedestals or supports as indicated at C, D and F. The pedestal B serves as a support for a pistol E, or other suitable form of fire-arm, while the pedestals C, D and F 70 serve as supports for the targets, generally indicated at 4. Any form of target may be employed, but preferably natural objects, such as imitations of birds, beasts, etc. The targets are suitably placed on top of the 80 pedestals C, D and F, and are in no way connected with the pistol or mechanism actuated thereby. A striking mechanism is however employed which is actuated by the pistol when this is correctly aimed, and this 85 striking mechanism serves the function of knocking the target off the pedestal, thus causing it to fall to one side or another and thereby indicate a hit.

To clearly illustrate the manner of accomplishing this result it may be stated that the pedestals C, D and F are identical in construction and that each consists of a tubular member 5 on the upper end of which the bird or other target employed 90 may be loosely placed. Mounted interior of each pedestal and guided thereby is a rod 6, which will hereinafter be termed the striker, and adapted to impart a vertical movement to one striker or another is a 100 substantially horizontally disposed arm 7, which is pivotally supported, as at 8, and an angularly adjustable directing arm 9. The inner end of this arm is secured in a tubular member 10, which is turnably supported in a bearing 11 of suitable construction. Forming an extension of the tubular member 10 is a cone shaped tube 12. A

suitable interlock is formed between the tube 12 and the tube 10 and they are therefore adapted to turn in unison, as will hereinafter be described.

5 The fire-arm, generally indicated at E, and here represented by a pistol, is supported by a vertically disposed tube 13. This tube is pivotally supported, as at 14, in the upper end of the cone shaped tube 12 and 10 permits vertical angular adjustment of the pistol when aiming the same, that is the pistol when grasped by the handle 15 may be rocked about the pivot 14 in a vertical direction, and a high or low aim on the tar- 15 get 4 may thus be taken. In the present instance three targets are shown, see Fig. 4, and it is therefore necessary that horizontal angular adjustment or pointing of the pistol shall be permitted. Such movement is possible as the pistol is supported by the tubes 10 and 12 and as these are turnably mounted in the bearing member 11, it can be seen that the pistol may be pointed so that any desired aim may be taken at the respective 20 targets C, D and F. The pistol is provided with a trigger 16 of any suitable construction, which is pivotally supported as at 17. The trigger is provided with a hammer 18 and this is propelled in a forward direction 25 by the action of a spring 19. Pivotally disposed within the magazine of the pistol, as at 20, is a lever 21. One end thereof is adapted to be struck by the hammer 18, while the opposite end thereof is adapted 30 to engage the upper end of a rod 22, which extends through the tube 13. The lower end of the tube 13 is practically closed, as at 23, to form a guide for the rod and to form a support for a helical spring 24, which engages a collar 25 and serves the function of normally supporting the rod 22 in a raised position. The lower end of the rod 22, which is particularly illustrated at 22^a, in Fig. 1, is adapted to align with the 35 upturned inner end 7^a of the arm 7 when the pistol is correctly aimed, and a rocking movement will thus be imparted to the arm 7 when the trigger is released, as the lever 21 will engage the rod 22 and force the same quickly in a downward direction. If the 40 points 22^a and 7^a are aligned, an impact will be transmitted to the arm 7 and this will then rock about the pivot 8. Again, if the arm 7 happens to be aligned with one of the 45 striking rods 6, upward movement will be imparted thereto and the target will be struck and knocked off the pedestal, thus indicating a hit.

One of the features of the present invention is the novel means employed whereby correct aiming is required before a target can be struck. First it is essential that the tubes 10 and 12 be turned to swing the directing arm 8 and the arm 7 into alignment 50 with the target aimed at. This is accom-

plished by turning the pistol horizontally until the correct aim is taken, and as such is the case alignment will be formed between the outer end of the arm 7 and the lower end of the corresponding striking rod 6. 70 Correct alignment in a horizontal direction with relation to the target is in this manner obtained, but before the target can be knocked off its pedestal or perch, it is also necessary that a correct vertical aim be 75 taken. This is obtained by rocking the pistol vertically about the pivot 14 and a correct aim is obtained when the lower end 22^a of the rod 22 aligns with the inner end 7^a of the arm 7, thus if the trigger is released 80 at this moment, it can be seen that movement will be imparted through the lever 21, rod 22 and arm 7, which imparts a rapid vertical impact movement to the striker rod 6, and that this will engage the lower side 85 of the target and knock it off the pedestal or perch, thus indicating a hit; the knocking off of the target being permitted as it is merely loosely placed on top of the pedestal and in no way connected thereto, and while 90 a bird is here illustrated, it is obvious that a soldier or any other suitable imitation of a natural target may be employed; the main feature being a target which may be knocked off the pedestal when the pistol is correctly 95 aimed.

The forward side of the tube 10 is vertically slotted, as at 30, see Figs. 1 and 5, to permit pivotal movement of the inner end 7^a of the arm 7. The lower end of this slot is 100 V-shaped, as at 31, and serves as a guide and a support for the directing arm 9. The inner end of this arm is flattened, as at 32, see Fig. 6, and is laterally slotted, as at 33. A screw 34 passes through the slot and secures the arm to a central lug 35 formed in the base of the tube 10. The slot 33 is important as it permits a slight horizontal turning movement of the directing arm 9 105 with relation to the tube 10, thus permitting adjustment of the same so as to permit the pistol to be aimed slightly to the right or left, or exactly aimed at the target as desired. A telescoping connection is formed 110 between the tubes 10 and 12, as shown in Fig. 1, thus permitting the tube 12 and the pistol carried thereby to be removed from the cover 2. The tubes or pedestals 5 are similarly removable with relation to the cover and as this is the case it can readily 115 be seen that it is possible to open the cover and to place the exposed parts of the mechanism interior of the base or box section A. A package convenient for transportation, storage or otherwise is thus formed, which 120 is exceedingly important when shipping and storing large quantities thereof.

The entire mechanism, including the striker, and that portion actuated by the fire-arm, is completely hidden from view. 125

This is also important as it adds considerable mystery to the general operation of the device. Projectiles, explosives, etc., are not employed, thus eliminating all danger of injury to the operator or spectators, and it may further be stated that the device does not only afford considerable amusement to the operator and spectators, but it is also educational as it permits practice in aiming and firing as ordinary gun or pistol practice.

While certain features of the present invention are more or less specifically illustrated, I wish it understood that various changes in form and proportion may be referred to within the scope of the appended claims, similarly that the materials and finish of the several parts employed may be such as the experience and judgment of the manufacturer may dictate or various uses may demand.

Having thus described my invention, what I claim and desire to secure by Letters Patent is—

1. In an apparatus of the character described a base member, a pedestal at one end thereof, an imitation pistol pivotally mounted on the upper end of the pedestal and adapted to impart a turning movement to the pedestal, said pistol being also vertically movable about the pivot, a rod depending from the pistol and entering the pedestal, a horizontal arm pivotally mounted within the base and supported by the pedestal, said arm having an upwardly extending inner end with which the dependent rod is adapted to align during vertical pivotal movement of the pistol, a second pedestal, a target adapted to be placed on the upper end thereof and loosely supported, and means in said pedestal for knocking the target off the pedestal, said means being actuated by the horizontally disposed arm when the arm aligns therewith.

2. In an apparatus of the character described a base member, a pedestal at one end thereof, an imitation pistol pivotally mounted on the upper end of the pedestal and adapted to impart a turning movement to the pedestal, said pistol being also vertically movable about the pivot, a rod depending from the pistol and entering the pedestal, a horizontal arm pivotally mounted within the base and supported by the pedestal, said arm having an upwardly extending inner end with which the dependent rod is adapted to align during vertical movement of the pistol, a second pedestal, a target adapted to be placed on the upper end thereof and loosely supported, a vertically disposed rod mounted in said pedestal, the upper end of which is adapted to engage the target and knock it off the pedestal, a trigger in the pistol, and means actuated by said trigger for imparting a vertical movement to the dependent rod and the striker rod in the pedestal.

estal and a rocking movement to the horizontal arm when the pistol is correctly aimed.

3. In an apparatus of the character described a base member, a pedestal turnably supported in one end thereof, a tube pivotally mounted in the upper end of the pedestal, an imitation fire-arm carried by said tube, said fire-arm and tube adapted to be rocked in a vertical direction and also adapted to impart a turning movement to the pedestal, a rod extending through the tube, a spring adapted to normally hold said rod in a raised position, a pivotally mounted lever in the pistol engageable with the upper end of the rod, and a trigger in the fire-arm engageable with said arm and adapted to impart movement to the arm and the rod.

4. In an apparatus of the character described a base member, a pedestal turnably supported in one end thereof a tube pivotally mounted in the upper end of the pedestal, an imitation fire-arm carried by said tube, said fire-arm and tube adapted to be rocked in a vertical direction and also adapted to impart a turning movement to the pedestal, a rod extending through the tube, a spring adapted to normally hold said rod in a raised position, a pivotally mounted lever in the pistol engageable with the upper end of the rod, a trigger in the fire-arm engageable with said arm and adapted to impart movement to the arm and the rod, a directing arm carried by the pedestal and horizontally positioned, said arm adapted to be turned in unison with the pedestal, a plurality of target supports in the opposite end of the base upon each of which a target is adapted to be loosely placed, a striker rod in each support, and an arm pivotally mounted on the horizontal arm and adapted to impart a vertical movement to any one of the striker rods when the fire-arm is correctly aimed and the trigger is actuated.

5. In an apparatus of the character described the combination with a pedestal, of means permitting turning movement thereof, an imitation pistol supported by the pedestal and adapted to impart a turning movement to the pedestal, a horizontally disposed directing arm secured to the pedestal, and means permitting horizontal angular adjustment of said arm with relation to the pedestal.

6. In an apparatus of the character described a base member, a plurality of vertically disposed pedestals arranged at one end of the base member said pedestals being tubular in formation, a striker rod vertically movable in each pedestal, a target adapted to be placed on top of each pedestal and adapted to be engaged by the striker rods and thereby knocked off the

pedestals, an imitation fire-arm supported at the opposite end of the base, a vertically disposed rod adapted to be reciprocated by the fire-arm, a horizontally disposed arm within the base and pivotally supported, means actuated by the pistol for turning the arm into alignment with a selected striker rod, an upturned end on said arm, and means permitting vertical swinging movement of the pistol to move the vertical rod carried thereby into alignment with the upturned end of the horizontal arm.

7. An apparatus of the character described, comprising an imitation pistol, a support therefor permitting horizontal swinging of the pistol and vertical horizontal swinging movement of the pistol, a second support, a target adapted to be placed thereon and loosely mounted, a striker rod in said support and engageable with the target, a second striker rod movable in unison with the pistol, a pivoted arm disposed below the striker rods, and means

for swinging the pivoted arm horizontally 28 in unison with the pistol.

8. An apparatus of the character described, comprising a base member, a target support and an imitation pistol support at opposite ends thereof, a target adapted to be loosely mounted on the target support, an arm attached at one end to the pistol support, a connection between the pistol and its support whereby the support and the arm may be swung horizontally by means 35 of the pistol so that the free end of the arm may be aligned with the target support, a second arm movable in unison with said arm and pivotally mounted thereon, a striker rod carried by the pistol and actuated by a trigger in the pistol, means 40 permitting vertical pivotal movement of the pistol on its support to bring the striker rod into alignment with the pivoted arm, and means actuated by the opposite end of 45 the pivoted arm when properly aligned to knock the target off its support.

CHARLES H. HELLING.
